PORTABLE WARDROBE

Robert B. Marsand, Bloomfield, N. J.

Application February 16, 1949, Serial No. 76,709

13 Claims. (Cl. 211—106)

1

This invention relates to wardrobes and garment hangers.

Wardrobes are known comprising a plurality of units arranged for assembly and disassembly. Wardrobes of this type have not come into general usage in part because of their complexity of construction, and the expense of manufacture thereof. Furthermore, many such wardrobes are awkward in form or shape, and heavy. It is especially desirable that wardrobes for use in automobiles be light and inexpensive to manufacture, and easy to assemble and disassemble in units.

It is an object of the present invention to provide an improved wardrobe of the type to be assembled or disassembled.

Another object of the invention is to reduce the expense and increase the ease of manufacture of such a wardrobe.

Other objects include providing such a wardrobe that is light, that may be easily assembled or disassembled, if desired one unit at a time, and that is especially well-adapted for automobile usage.

These and other objects, advantages, and novel features of the invention will become more fully apparent from the following description and the accompanying drawing in which like parts have like reference numerals and in which:

Fig. 1 is a perspective view of a wardrobe of the invention assembled but with some of the units pivoted open;

Fig. 2a is a face view of a portion of Fig. 1 to show the manner of construction of a pivot opening in Fig. 1;

Fig. 2b is a face view of an alternative construction of the pivot opening of Fig. 2;

Fig. 3 is a perspective view of the wardrobe of Fig. 1 assembled and ready for carrying as a whole or for storing; and

Fig. 4 is a perspective view of an alternative fastener for the wardrobe.

In accordance with the invention, I arrange a base unit and a side unit together, the base unit having openings or wire loops. A frame unit, preferably entirely of wire, has two end portions projecting to engage or fit into the openings, the frame itself acting as a spring to hold the frame pivotally in the openings. The frame thus pivots toward or away from the side unit, and may be held in assembly as more fully disclosed hereinafter. As will be seen, the assembled wardrobe is readily held in the trunk or floor of an automobile, if desired.

In accordance with a further feature of the in-

2

vention, I provide the base unit with openings in each of which may be hung an ordinary hanger with a garment thereon. Then a corresponding garment frame may be pivoted into carrying position with the garment folded thereover.

Referring now more particularly to Fig. 1, a wire base unit 6, rectangular in form, has openings 8 therein along the sides 7 at equally spaced intervals. A side unit 10, also rectangular and constituted by a top wire portion 5 and side wire legs 3, is attached rigidly to one side of the wire base unit 6. An inverted U-shaped frame 12, preferably of wire, having a top member 42 and side legs 44, has oppositely facing end portions 14 which are inserted respectively in one of a pair of openings 8, the wire frame 12 being placed under stress with such insertion and thus serves also as a spring. The end portion 14 may include a bend or single corrugation to be engaged more securely in the opening. An inverted U-shaped frame unit 20 similar to frame unit 12 engages a similar pair of openings 8. It will be apparent that more than one frame similar to frame 12 may be engaged in similar pairs of openings 8, if desired. Openings 9, which may be similar to openings 8, are provided in a central wire 45 of base member 6. There is preferably one opening 9 for each pair of openings 8 and preferably spaced slightly closer to side unit 10 than the line through the corresponding pair of openings 8.

In Fig. 2a the opening 8 is shown as formed by a loop in base unit 6, whereas in Fig. 2b is shown an alternative construction of an opening 8' which may be used in lieu thereof, formed by an arcuate nearly complete circular bend in the wire of base unit 6.

In operation, the frames 12, 20 may be selectively disengaged from the openings 8 by swinging or pivoting other frames down, and on reaching the frame which it is desired to remove, by increasing the stress upon the side portions thereof to bring the sides somewhat together. The end portions 14 are thereby freed from the openings, and the selected frame may be withdrawn from the wardrobe. It will be apparent that the frames 12 and 20 are in themselves each a spring, as well as a garment frame over or upon which garments may be hung. Frame 20 is preferably rectangular, so that when pivoted into substantial parallelism with side unit 10, it may be held in position with spring clips 22 or the like, as shown in Fig. 3. In Fig. 4, as an example, is shown a substitute for the spring clips consisting of an elastic band 24 having snap fasteners 26, 28. Frame 12 may have a different shape depending

upon the garment to be hung or folded thereover. A carrying handle 30 may also be provided which may assume the position shown in Fig. 1 when not in use, or the position shown in Fig. 3 when used to carry the assembled wardrobe. Base unit 6 may be engaged by any suitable means (not shown) in the floor of an automobile or in the bottom of the trunk compartment thereof, preferably in a detachable manner. Thus individual frame units such as 12 or 20 with the garments hung thereon, may be selectively removed by the traveler and carried freely about, without removing the entire wardrobe. If desired, a removable cloth cover 36 may be provided which covers the side unit 10, the base 6, and has sufficient surplus material to extend over the frame unit 20 and the top of the wardrobe when assembled thereby to protect the garments within against dust and dirt.

Since many garments are longer than the proposed 16 inch dimension of the garment frames, the openings 9 may be provided, in which an ordinary hanger 32 of the type in commercial and common daily use may be received. The garment, for example a coat 34, is hung over the hanger and extended on top of the frame 20 engaged in the openings corresponding to the opening 9 in which the hanger is received. As is apparent from the drawing when the frame 20 is pivoted to the storing or carrying position parallel to the plane of side unit 10, the garment hangs over frame 20 in a fold, where it is draped and firmly held without crushing or creasing because of the spacing of the openings 9 slightly toward the plane of side unit 10 from the pair of openings 8. Of course, if the garment and frame unit are to be removed together from the base unit, the hanger 32 is disengaged from opening 9 as well as garment frame 20 from openings 8. Alternatively, the garment 34 may be removed from the wardrobe, by removing the hanger without removing or disengaging frame 20. There may be as many garments anchored by means of hangers to the base 6 as there are frames or units 12, 20, it being understood that there are as many openings 9 as there are frames or units 12, 20. Only one such garment hanger is shown in Fig. 1 in the interest of simplifying the drawing.

It will thus be apparent that I have devised a wardrobe which is not only novel, but light in weight and exceedingly inexpensive to manufacture. It will be noted in this regard, that the entire wardrobe, except for the cloth covering, may be made of any inexpensive material, but is especially well adapted to be manufactured of wire. Thus the construction may be made sturdy yet light and inexpensive. The wardrobe of the invention is especially useful in connection with automobile travel, and permits the easy removal or storage of single selected garments with ease.

Although the invention has been described with particular reference to the use of wire for the various elements of the wardrobe, it should be understood that the invention is not limited to the use of wire, since other materials such as plastic or wood may be used effectively to achieve the desired results.

What I claim is:

1. A wardrobe assembly comprising a base unit and a side unit each made from wire, the sides of said base unit being continuations of the legs of said side unit, an inverted U-shaped frame having legs with projecting end portions facing in opposite directions, said frame being at least

in part a spring, said base unit comprising a rectangular frame having one pair of opposite sides looped at certain points to provide openings receiving said end portions and wherein said portions are pivotally engaged under stress of said spring with insertion of said end portions in said openings.

2. A wardrobe assembly formed of wire comprising a rectangular base unit, a side unit having members connected to the base unit and lying substantially in a plane, and an inverted U-shaped garment frame having two projecting end portions facing in opposite directions, said frame being at least in part a spring, said base unit having sides which are coiled to provide a pair of openings receiving said end portions and wherein said end portions are pivotally engaged under stress of said spring with insertion of said end portions therein, said openings being arranged in a line parallel to the plane of said side unit whereby said frame may pivot into parallelism with said side unit plane and away therefrom and whereby stress on said frame may be exerted to release it from said base unit.

25 3. The wardrobe assembly claimed in claim 2, said openings being loops in said sides of the base unit.

4. The wardrobe assembly claimed in claim 2, said openings being arcuate nearly complete circular bends in said sides of the base unit.

5. The wardrobe assembly claimed in claim 2 further adapted to receive a garment hanger, said base unit having a central wire with openings in which said hanger may be engaged.

35 6. The wardrobe assembly claimed in claim 2 further adapted to receive a garment hanger, said base unit having a central wire extending parallel to the sides of the base unit, said central wire also being coiled at a point intermediate its ends to provide an opening for a garment hanger.

7. The wardrobe assembly claimed in claim 6, said openings being loops in said wire portions.

8. In a wardrobe assembly having a wire base unit and a wire side unit each lying substantially in a plane substantially normal to the plane of the other, the sides of said base unit being continuations of the legs of said side unit, the combination comprising an inverted U-shaped garment frame having legs with projecting end portions and being at least in part a spring, oppositely disposed portions of the sides of said base unit being coiled to provide a pair of openings to receive said end portions and wherein said end portions are pivotally and yieldably engageable under stress of said spring with insertion of said end portions therein, the said pair of openings being in a line substantially parallel to said side unit plane whereby said frame is easily assembled or disassembled from said base and on assembly is pivotally engaged thereto to pivot substantially into parallelism with said side unit plane or away therefrom substantially into parallelism with said base unit plane.

50 9. The combination claimed in claim 8 further adapted to receive a garment hanger, said base unit having a wire intermediate the sides thereof and lying in the same plane therewith, said wire being coiled to provide an opening corresponding to said pair of openings and symmetrically positioned therebetween but spaced closer to said side unit plane than said pair of openings.

10. A garment hanger comprising a rectangular metal frame base unit having spaced

75

horizontal rod-like members interconnected at their ends by other rod-like members, a metal frame unit attached to one side of said base unit, another metal frame unit attached to the other side of said base unit, at least one of said frame units being pivotally mounted on said base unit, and means directly mounted on a horizontal rod-like member of said base unit for supporting a garment hanger.

11. A garment hanger comprising a rectangular-shaped metal frame base unit having spaced horizontal rod-like members interconnected at their ends by other rod-like members, a metal frame unit attached to one side of said base unit, another metal frame unit attached to the other side of said base unit, at least one of said frame units being pivotally mounted on said base unit, and means detachably mounted on said base unit at a point intermediate the ends of said horizontal rod-like members for supporting a garment.

12. A garment hanger comprising a pair of spaced metallic frame units secured to a metallic base frame unit and pivotally mounted on said base unit relative to each other, said base unit having four rod-like members interconnected at their ends to form a rectangular frame, and means on said base unit at a location intermediate the ends thereof for supporting a garment.

13. A garment hanger comprising a rectangu-

30

lar-shaped metal frame base unit having spaced horizontal rod-like members interconnected at their ends by other rod-like members, a metal frame unit attached to one side of said base unit, and another metal frame unit attached to the other side of said base unit, at least one of said frame units being pivotally mounted on said base unit, said base unit having a metal strip connected to both the horizontal members at an angle thereto, said strip having an eyelet for receiving a garment hanger.
